United States Patent Office

Des. 181,890
Patented Jan. 7, 1958

181,890

TRUCK BODY

Wallace B. Updegrove, Boyertown, Pa., assignor to Morysville Body Works, Inc., Boyertown, Pa.

Application June 29, 1956, Serial No. 42,094

Term of patent 14 years

(Cl. D14—3)

Fig. 2.

The dominant feature of my design resides in the full lines shown in the drawings.

I claim:

The ornamental design for a truck body, substantially as shown and described.
